UNITED STATES PATENT OFFICE.

WINFIELD B. PHILLIPS, OF FENTON, MICHIGAN.

DESIGN FOR A SCREEN-DOOR FRAME.

SPECIFICATION forming part of Design No. 23,319, dated May 29, 1894.

Application filed April 19, 1894. Serial No. 508,218. Term of patent 7 years.

To all whom it may concern:

Be it known that I, WINFIELD B. PHILLIPS, of Fenton, in the county of Genesee and State of Michigan, have invented a new and useful Improvement in a Design for Screen-Door Frames, of which the following is a specification.

This design has for its object to provide an ornamental screen door frame which presents a characteristic appearance to the eye.

The design consists in a screen door frame having corners of the panel provided with diagonal sections or lines connected by inclined ornamental rod-like sections or lines.

The design is illustrated by the accompanying drawing, in which the figure is an elevation of the screen door frame.

In the drawing the letters A indicate the rectilinear sides, the letters B the rectilinear ends, and the letter C an intermediate traverse which divides the whole panel into two sections D D. The panel is provided at corners with diagonal sections or lines E and F, which are connected by inclined ornamental rod-like sections or lines G.

The design provides a screen door frame which is handsome and ornamental.

What I claim is—

The design for a screen door frame, substantially as shown and described.

WINFIELD B. PHILLIPS.
